HOISINGTON, KANSAS.

ATTACHMENT FOR WEIGHING-SCALES.

No. 820,947.

Specification of Letters Patent.

Patented May 22, 1906.

Application filed June 28, 1905. Serial No. 267,470.

To all whom it may concern:

Be it known that we, JOHN BARRY and MICHEAL L. SHAUGHNESSY, citizens of the United States, residing at Westphalia, in the county of Anderson and State of Kansas, have invented certain new and useful Improvements in Attachments for Weighing-Scales, of which the following is a specification.

Our invention relates to attachments for weighing-scales, and more especially to attachments for even-balance scales which will indicate to the operator at a glance how much in ounces and fractions thereof the weight of the commodity exceeds or falls short of the proper weight; and our object is to produce an attachment of this character which operates efficiently and reliably and can be manufactured and applied to any of the approved types of scales of the even-balance type now on the market.

With this object in view the invention consists in certain novel and peculiar features of construction and organization, as hereinafter described and claimed, and in order that it may be fully understood reference is to be had to the accompanying drawings, in which—

Figure 1 represents a back view of an even-balance scale equipped with our attachment. Fig. 2 is a detail front view of the attachment with its front plate broken away to expose parts otherwise hidden. Fig. 3 is a top plan view of the attachment disposed as shown in Fig. 1, said figure also showing part of the contiguous pan of the scale.

In the said drawings, 1 indicates the base; 2, the frame rising therefrom; 3, the balance-frame pivotally supported within frame 2; 4, frames pivotally pendent from the ends of the balance-frame, and 5 the pans movable vertically with said frames. As represented by the drawing, Fig. 1, the pan on the left hand is the weight pan or rest and the one to the right the commodity-pan. The scale is equipped with a scale-beam (not shown) carried by frame 3 at its front side or the side adjacent to the clerk behind the counter, and adjustable on this scale-beam is a poise 6. Any other type of even-balance scale may be employed in lieu of that described.

7 indicates an angle-arm provided with a

horizontal slot 8, and in a lower plane the outer end of the arm is bent back upon itself 55 to form the vertical sleeve 9, a screw 10 extending through the body of the arm and its end for the purpose of drawing them closer together; so as to constitute a clamp.

11 indicates a standard depending from 60 an angle-bracket 12, and 13 indicates a plate secured to said angle-bracket and having its upper and lower margins curved by preference, the upper end of the plate being bent upward and rearward by preference and 65 bearing at its front side indicia to represent ounces or fractions thereof, the central mark representing the neutral or "0" point. When viewing the scale from inside the counter, the numbers or figures from "0" to 70 "3" to the right indicate underweight and from "0" to "3" to the left indicate overweight, as in Fig. 2; it being understood that the upper portion of the plate 13, herein-after termed the "scale-plate," is pitched 75 at an angle, as described; in order that the salesman may more easily read it.

14 indicates screws disposed in the same horizontal plate at opposite sides of and equal distances from the center of plate 13, 80 and 15 is a plate engaged and clamped by said screws against the sleeves 16, mounted on screws 14 between the scale-plate and plate 15.

17 indicates an arbor journaled at its ends 85 in plates 13 and 15 and disposed centrally thereof and axially of the indicia of the scale-plate, and secured rigidly on said arbor is an index-finger 18, having a longitudinal slot 19 in its lower end. A sliding weight 90 20 engages finger 18 and is held thereon by a clamping-screw 21, extending through said slot. Because of this construction weight 20 can be adjusted upward or downward to decrease or increase its leverage, so that it 95 shall instantly respond to movement of the part of the scale adapted to operate it, as hereinafter explained.

22 is a pin projecting from the index-finger at one side of its arbor 17 and pivotally connected by a depending link 23 and an upwardly-projecting link 24 to the inner ends of a pair of levers 25 and 26, respectively, said levers being secured on pins 27 and 28, respectively, journaled in the scale-plate and 105 plate 15. The outer ends of said levers are

enlarged or headed to receive the set-screws 29, lock-nuts 30 engaging the screws and said levers to lock the former at the desired points of adjustment.

5 To assemble the attachment in proper relation with the scale, the angle-arm 7 is arranged with its slotted portion against frame 2 and is secured therein at the desired point of adjustment by clamping-screws 31. The 10 standard 11 is then fitted in sleeve 9 until the levers are approximately at equal distances from the plane of the weight-pan, the clamping-screw 10 being then manipulated to clamp the standard in such relation. The set-screws 29, one of which stands above and the other below the outer portion of the weight-pan, and therefore in the path of its movement, are adjusted so that they shall be equal distances from the pan when balanced and 15 are locked in such relation by the lock-nuts.

When the weights are placed upon the weight-pan, and thereby cause it to move downward, it imposes downward pressure on the underlying set-screw and swings the index-finger to the right of the operator until its movement is arrested by contact with the right-hand stop 32, projecting forwardly from the scale-plate, said stop being preferably a portion of said plate bent forwardly.

20 The commodity is now placed upon the commodity-pan, and when its weight is within three ounces of the weight on the weight-pan the latter has been moved upward a sufficient distance to permit the index-finger to register 25 with the "3" mark at its right-hand side, so that it shall indicate that the commodity is only three ounces underweight and the operator will know approximately how much of the commodity should go on the scale to 30 bring it to a balance, it being understood that as the weight-pan continues to rise it is followed upward by the underlying set-screw, the movement of the set-screw being induced, of course, by the weighted index-finger. When 35 the scale is brought to approximately an exact balance, the index-finger registers with the "0" or neutral mark. When the weight of the commodity exceeds that on the weight-pan, the latter will rise and impose upward 40 pressure on the upper set-screw 29, and thereby cause the index-finger to swing to the left so as to register in ounces or fractions thereof the excess weight of the commodity, this movement being limited by the left-hand 45 stop 32. The operator then removes a part of the commodity, so as to bring the scale to 50 balance, this being indicated by the swinging of the index-finger back to neutral or "0" point.

55 60 65 60 It is obvious, of course, that the attachment can be rendered more or less sensitive to the movement of the balance-frame by raising or lowering the slide on the index-finger, as hereinbefore referred to, the elevation of the slide increasing and its depression de-

creasing the leverage of the scale-beam on the index-finger. The attachment by the adjustment on the slotted arm 7 of the bolts 31 and the vertical adjustment of the standard 11 in sleeve 9 can be attached to scales of varying 70 proportions.

It will be understood, of course, that it is immaterial on what part of the scale-frame said slotted arm is secured and that it is likewise immaterial whether movement shall be 75 imparted to the index-finger through the medium of one of the pans, the balance-frame itself or a part of the frame movable with said balance-frame, though we prefer the construction illustrated and described. By loosening 80 the clamping-screw 10 the scale-plate can be turned to face in the direction most convenient to the operator and then clamped in such position by the proper manipulation of the clamping-screw, it being understood, 85 of course, that the scale-plate must not be turned sufficiently to withdraw the set-screws 29 out of the plane of vertical movement of part designed to contact with them.

From the above description it will be apparent that we have produced an attachment for even-balance scales possessing the features of advantage enumerated as desirable.

Having thus described the invention, what we claim as new, and desire to secure by Letters Patent, is—

1. The combination of a scale, an arm carried by said scale, a scale-plate carried by said arm and provided with indicia numbered from "0" upward in opposite directions, a lever overhanging a movable part of the scale, an index-finger pivoted to the scale-plate, and a link pivotally connecting said lever and index-finger to transmit movement from one to the other.

105 2. The combination with a scale of an attachment, comprising a supporting-arm secured to a fixed point of the scale, a scale-plate supported from said arm, having indicia numbered upward in opposite directions 110 from a "0" or neutral point, an index-finger pivoted to the scale-plate, a pair of levers pivoted to the scale-plate and linked to the index-finger and disposed above and below a movable part of the scale so as to be moved 115 downward by said movable part when the commodity upon the scale is under weight, and upward by said part when the commodity on the scale is over weight, and means to cause the index-finger to yieldingly resist such rise or fall of the balance-frame and to dispose and hold it at the neutral point of the scale-plate when said balance-frame is balanced.

120 125 130 3. The combination with a scale, of an attachment, comprising a supporting-arm secured to a fixed point of the scale and longitudinally adjustable thereon, a scale-plate supported from said arm, having indicia numbered upward in opposite directions

- from a "0" or neutral point, an index-finger pivoted to the scale-plate, a pair of levers pivoted to the scale-plate and linked to the index-finger and disposed above and below a movable part of the scale so as to be moved downward by said movable part when the commodity upon the scale is under weight, and upward by said part when the commodity on the scale is over weight, and means to 5 cause the index-finger to yieldingly resist such rise or fall of the balance-frame and to dispose and hold it at the neutral point of the scale-plate when said balance-frame is balanced.
- 15 4. The combination with a scale, of an attachment, comprising a supporting-arm secured to a fixed point of the scale, a scale-plate vertically adjustable on said arm, and having indicia numbered upward in opposite 10 directions from a "0" or neutral point, an index-finger pivoted to the scale-plate, a pair of levers pivoted to the scale-plate and linked to the index-finger and disposed above and below a movable part of the scale so as to be 20 moved downward by said movable part when the commodity upon the scale is under weight, and upward by said part when the commodity on the scale is over weight, and means to cause the index-finger to yieldingly 25 resist such rise or fall of the balance-frame and to dispose and hold it at the neutral point of the scale-plate when said balance-frame is balanced.
- 30 5. The combination with a scale, of an attachment, comprising a supporting-arm secured to a fixed point of the scale, a scale-plate supported from said arm having indicia numbered upward in opposite directions from a "0" or neutral point, an index-finger 35 pivoted to the scale-plate, a pair of levers pivoted to the scale-plate and linked to the index-finger and disposed above and below a movable part of the scale, vertical set-screws secured in the outer ends of said levers, the 40 upper screw to be engaged by the movable part of the scale when it rises a sufficient distance and the lower one to be engaged by said part when it descends a suitable distance, and means to cause the index-finger to yieldingly 45 resist such rise or fall of the balance-frame, and to dispose and hold it at the "0" or neutral point of the scale-plate when said balance-frame is balanced.
- 50 6. The combination with a scale of an attachment, comprising a supporting-arm secured to a fixed point of the scale, a scale-plate supported from said arm and having indicia numbered upward in opposite directions from a "0" or neutral point, an index-finger 55 pivoted to the scale-plate, a pair of levers pivoted to the scale-plate and linked to the index-finger and disposed above and below a movable part of the scale so as to be moved downward by said movable part when the commodity upon the scale is under weight, and upward by said part when the commodity on the scale is over weight, and means to cause the index-finger to yieldingly 60 resist such rise or fall of the balance-frame.
- 65 7. The combination of an even-balance scale, a horizontally-slotted arm, screw-bolts carried by a fixed part of the scale-frame and extending through the slot of said arm to 70 clamp the latter at the desired point of adjustment, a vertical clamping-sleeve at the opposite end of said arm, a vertical standard clamped in said sleeve, a scale-plate rigid with and supported from said standard and 75 having indicia numbered upward in opposite directions from a "0" or neutral point, an index-finger pivoted to the scale-plate, a pair of levers pivoted to the scale-plate and linked to the index-finger and disposed above and 80 below a movable part of the scale so as to be moved downward by said movable part when the commodity upon the scale is under weight, and upward by said part when the commodity on the scale is over weight, and means to cause the index-finger to yieldingly 85 resist such rise or fall of the balance-frame and to dispose and hold it at the neutral point of the scale-plate when said balance-frame is balanced.
- 90 8. The combination with an even-balance scale having a suitable fixed frame, a balance-frame mounted thereon, frames pivotally suspended from the end of the balance-frame, pans movable vertically with said 95 pivotally-suspended frames, a longitudinally-slotted arm secured to the scale-frame below the pivotal point of the balance-frame, a scale-plate supported from said arm having indicia numbered upward in opposite directions from a "0" or neutral point, an index-finger pivoted to the scale-plate, a pair of levers pivoted to the scale-plate and linked to the index-finger and disposed above and below one of the movable pans, so as to be 100 moved downward by said pan when the commodity on the other pan is under weight, and upward by said first-named pan when the commodity in said other pan is over weight, and means to cause the index-finger to yieldingly 105 resist such movement.
- 110 9. The combination with an even-balance scale, of a scale-plate bearing a fixed relation to the scale-frame and provided with indicia numbered from "0" upward in opposite directions, a pair of levers pivoted to the scale-plate and disposed above and below and within the range of movement of a movable part of the scale, an index-finger pivoted to the scale-plate and linked to said levers, and 115 means to hold the index-finger yieldingly in a vertical position and adapted to resist the rise or fall of the movable part of the scale in its balancing movement.
- 120 10. The combination of a scale, an arm 125
- 130

carried by said scale, a scale-plate carried by
said arm and provided with indicia num-
bered from "0" upward in opposite direc-
tions, a lever underlying a movable part of
5 the scale, an index-finger pivoted to the scale-
plate, and a link pivotally connecting said
lever and index-finger to transmit movement
from one to the other.

In testimony whereof we affix our signa-
tures in the presence of two witnesses.
